UNITED STATES PATENT OFFICE.

HARRY A. RITTER, OF CHICAGO, ILLINOIS.

CHECK-INDORSING MACHINE.

Application filed September 10, 1920. Serial No. 409,355.

To all whom it may concern:

Be it known that I, HARRY A. RITTER, a citizen of the United States, residing at Chicago, in the county of Cook and State of Illinois, have invented certain new and useful Improvements in Check-Indorsing Machines, of which the following is a specification.

My invention relates to an apparatus for indorsing or stamping checks or similar instruments and its novelty consists in the construction and arrangement of parts as will be more fully hereinafter described.

The apparatus of my invention is especially useful in banks, mercantile houses, and the like for cancelling, marking, and indorsing checks, stamps, and like articles. Especially is it useful where large quantities of these various articles have to be marked.

20 An object of my invention is to provide an apparatus which is simple, practical, accessible, and one which will accomplish its purposes in an expeditious manner.

Another object of the invention is to provide an apparatus of the character herein described where it is desirable to change certain marking data from time to time, my invention being directed to simple and quickly changed means therefor.

30 A further object is to provide a machine wherein the various articles to be marked may be passed through the machine mechanically.

A still further object is to provide an apparatus for marking or cancelling checks in an efficient, simple, and expeditious manner.

The above recited and other objects of my invention will be apparent from the following description and will be particularly 40 pointed out in the appended claims.

The preferred embodiment of my invention is shown in the accompanying drawings wherein—

Figure 1 is a side elevation of the preferred embodiment of my invention with some of the parts broken away to show some of the details.

Figure 2 is a front elevation view with parts of frame in front of and above rollers broken away.

Figure 3 is a vertical, sectional view through the dater or the stamp roll.

Figure 4 is a perspective view of the dater or stamp roll; and,

55 Figure 5 is a detail view, partially in sec-

tion of a portion of the machine showing a latching mechanism.

The machine as shown in the drawings includes a main frame having uprights 1, and a side plate 1^a. A hooded member 2 is suitably secured to the frame and overlies certain of the mechanisms of the machine. 3 is a motor support suitably fastened to the base of the frame on which is mounted a motor base 4, carrying an electric motor 5, 65 the shaft of which supports a pulley 6. Suitably journaled in the side plate 1^a (Figure 2) is a short shaft 9 carrying at its outer end a large grooved pulley 8, and on its inner end a smaller pulley 10, which latter 70 pulley is also grooved. A belt 7 transmits power from the motor pulley 6 to the large pulley 8.

Suitably supported in the upper portion of the frame is shaft 13, on which is mounted a roller 12, which roller may be made of any suitable material, such as wood, metal, hard rubber, or fiber, and which roller has a series of grooves formed in the periphery thereof. A belt 11 passing over pulley 10 80 drives the roller 12. The frame is provided with slotted blocks 19, one on each side of the frame carrying a shaft 17. Springs 20 are interposed in the slotted members and tensioning devices 21 may be regulated to 85 vary the tension of the springs against the shaft 17. A similar set of slotted members adjacent the first set but placed below the first set, carry blocks 22, springs 23, and tensioning members 24, all of which function to support a shaft 18. On the shaft 17 is mounted a roller 15, while shaft 18 supports a roller 16. About the roller 15 and roller 12 pass belts 14 carried in grooves 15' which belts are preferably of some suitable 95 friction material. The roller 16 has at one end a series of grooves 16' formed therein. These grooves underlie similar grooves in the roller 15. The belts 14' pass around roller 12 and roller 16 with one leg of said 100 belts contacting roller 15. With the above construction it will be noted that rollers 15 and 16 are driven by belts 14 and 14' from roller 12, so that any motion imparted to roller 12 will be transmitted to the rollers 15 105 and 16, and by reason of belts 14' the speed of rollers 15 and 16 will be the same.

The hooded member 2 is supported on the frame at one end thereof and extends above the frame. Suitably journaled in the side 110

walls of the member 2 is a shaft 25^a carrying a roller 25, which roller is positioned to be frictionally driven from roller 15. Intermediate the end walls of the member 2 is a downwardly extending wall 62. Referring to Figure 3, it will be observed that mounted in the wall 62 is a spindle 53, on which is positioned a freely rotatable roller 50 having grooves 50' and 67 therein. Within 10 the spindle 53 is a shaft 51, one end of which extends beyond the outer end of spindle 53 carrying a disk 52, and the other end of the shaft being enlarged and provided with a slot 66.

15 The stamp roller or dater includes a pair of disks 27 and 27' (Figure 4) which are held in spaced parallel relation by bars 38 and 39. The bar 38 serves as a mounting to which is hinged or otherwise suitably secured a plate 37 arranged in such manner that said plate may swing about bar 38 as an axis. The other edge of the plate is provided with spring clips 60, which when the plate is moved into printing position, spring 25 or snap over the bar 39 to hold the plate 37 in operative position. On the outside of the plate 37 is a pad 37^a on which may be applied a certain portion of the matter to be printed by the machine. The plate and 30 the pad have a slot 61 therethrough for the purpose of permitting the matter which is selectively set up as hereinafter described, to project through the slot and to form a part of the matter to be printed. A shaft 35 is keyed or otherwise secured to the disk 27, while the other end of the shaft is connected by means of the pin 55 with a sleeve or bushing 54, which bushing carries the disk 27'. The outer end of the bushing 54 35 is provided with a recess 64, while the end of the shaft 35, which extends beyond disk 27 is flattened to interfit with the slot 66 in the shaft 51, so as to rotate therewith under certain conditions. A hollow member 47 is threaded into an opening in the wall 65 of the member 2. A cap 48 is threaded onto the end of the member 47, while a plunger 57 is mounted within the member 47 to have lengthwise movement 45 therethrough. A spring 58 cooperates between the cap 48 and the body of the plunger 57 to maintain the plunger inwardly of the wall 65, as viewed in Figure 3. The plunger is provided with a head 56 whereby to withdraw the same. The other end of the plunger has a reduced portion 56' adapted to cooperate with the recess 64 in the bushing 54, and thereby maintain the shaft 35 and its associate parts in operative relation 50 to as shown in Figure 3 of the drawings.

A frame 35^a is splined on shaft 35 as shown in Figure 3, and is held in position thereon by screws or other elements 40 passing through the shaft. The frame 35^a 55 carries a plurality of printing bands which

carry outstanding projections 36, 36^a, 36^b, 36^c and 36^d. Said bands are slidable circumferentially on the frame 35^a. The outer ends of the several projections bear numerals, letters, or other characters which may 70 be useful in being arranged in selected combinations so as to print dates or the like in conjunction with the matter on pad 37^a.

The members 36 may be inscribed with the names of the months, 36^a with the years, 75 36^b with numbers. If it is desired to employ other members to fix other marks, such as A. M. or P. M. or other specific marks, such may be carried on members 36^c and 36^d, so that when once arranged in the selected 80 order, the order will be maintained as long as desirable. To change a date, the stamp roller or dater as shown in Figure 4 may be taken from the apparatus by pulling out the plunger 57 which frees one end of the shaft, 85 so that the whole dater may be removed. The cover 37 is opened and the various members 36 manipulated to give the desired date or other marking required. When this has been set up, the cover is closed, so that the 90 selected data is on the projections of members 36 which extend through the slot 61 in the cover 37, whereupon the dater may be returned to operative position, which is that shown in the Figure 3. 95

Belts 26 pass around rollers 25 and 50 in the grooves 50' so that any motion imparted to roller 25 will be transmitted to roller 50. In the periphery of the disks 27 and 27' are inserted frictional members or 100 tires 28, which however do not extend completely around the edges of the disks. Under certain conditions these tires have frictional engagement with the roller 16.

Referring to Figures 3 and 5, it is to be 105 noted that the disk 52 carries an outwardly extending stop 34. Extending between the partition walls 62 and 65 of the member 2 is a shaft 30 carrying inwardly of the wall 62 a depending trip finger 29, which extends downwardly between belts 14' and 26, the grooves 67 in roller 50 and 68 in the roller 25 permitting swinging of the finger. Outwardly of the wall 62 is an arm 31 keyed to the shaft 30, arranged in angular relation 110 with respect to the finger 29. The free end of the arm 31 has a hook which normally engages the stop 34 on the disk 52. The arm 31 carries a lug 32 through which passes one end of a coil spring 33, the other 115 end of the spring being fastened to the stop 34. 120

An inking roller 41 is carried on a shaft 42 supported in suitable bearings in member 2. The inking roller 41 is maintained in 125 contact with the dater or stamp roller by means of springs 44 and tensioning devices 45 similar to those described in connection with shafts 17 and 18.

The operation of the device is as follows: 130

The motor being set in motion through the operation of a suitable switch, the roller 12 is rotated. This causes rotation through the belts 14 and 14' of the rollers 15 and 16. 5 Roller 25 is rotated through frictional engagement with roller 15, and rotation of roller 25 through belts 26 imparts rotation to the roller 50. The pile of checks or other matter to be stamped may be placed on the 10 table 46 and deposited one by one on the belts 14 and 14'. Thereupon, these belts acting as apron conveyors carry the checks through the machine between the rollers 15 and 25 and 16 and the dating roller. As 15 soon as a check engages the trip finger 29, this is swung in a counter clockwise direction (Figure 5) a sufficient distance to permit the check to pass thereunder. The movement of the trip finger 29 raises the arm 31 and its 20 hooked end out of engagement with the stop 34. Thereupon the stamp or dater roller rotates by gravity because of its overbalanced position by reason of the cover 37 and the pad 37^a, until such time that the tires 25 28 contact the roller 16, which contacting is timed with the movement of the check so that the matter to be printed on the check will be printed in the correct position thereon, the pad 37^a and its associated members 36 30 making the impression thereon on the check as the same is carried along between the belts 26 and 14'. Continued association with rollers 16 feeds the check outwardly of the machine into the receiving basket 49. 35 The rotation of the stamp roller continues until the hooked end of the arm 31 again engages the stop 34 on the disk 52. Whereupon the stamp roller is brought to rest. In this position the mutilated portion of the 40 tires are out of contact with the roller 16. The spring 33 acts to draw the arm 31 into position to engage the stop 34, which movement also returns the trip finger 29 to bring the same into the path of movement of the 45 checks to be acted on by the next check passing through the machine. The inking roller 41 inks the pad 37^a after the same has made an impression on the check and prior to the time that the roller is released to print 50 the next check.

It may be observed that my invention contemplates a machine for cancelling checks and the like wherein the checks are carried through the machine mechanically, doing 55 away with the feeding of the individual checks into the printing mechanism. The dater is one which is readily removed, changed, and replaced, thus facilitating the cancelling, indorsing, or other marking of

the checks. By reason of the fact that the 60 checks are carried through the machine by the belts, the efficiency of the machine is greatly increased over the present type of cancelling machines. A further advantage of my machine resides in the ease in which 65 the date may be changed.

While I have described more or less precisely the details of my invention, I do not wish to be understood as limiting myself thereto, as I contemplate changes in form, 70 the proportion of parts and the substitution of equivalents as circumstances may suggest, or render expedient, without departing from the spirit of my invention.

I claim:

1. In an indorsing machine, an endless conveyor comprising a plurality of bands, roller means for driving said bands, a pair of rollers driven by said bands, certain of said bands being placed to engage with said 80 roller means and one of said rollers and certain of said bands being placed to engage with said roller means and both of said rollers and other endless conveyor means and stamping means driven from said 85 rollers.

2. In an indorsing machine, an endless conveyor, roller means for carrying same, a second endless conveyor driven synchronously with said first conveyor, roller means for carrying said second conveyor, a shaft upon which one of said last mentioned roller means is freely rotatable, said shaft having trip mechanism cooperating therewith for causing rotation of said shaft in response 90 to movement of a member carried by one of said conveyors and a rotary printing element operated by said shaft. 95

3. In an indorsing machine, an endless conveyor, roller means for carrying same, a second endless conveyor driven synchronously with said first conveyor, roller means for carrying said second conveyor, a shaft upon which one of said last mentioned roller means is freely rotatable, said shaft having trip mechanism cooperating therewith for causing rotation of said shaft in response to movement of a member carried by one of said conveyors and a rotary printing element operated by said shaft, said 100 printing element being a drum spring pressed into locking engagement with one end of said shaft whereby to be readily removable and replaceable. 110

Signed at Chicago, Illinois, this 4th day 115 of September, 1920.

HARRY A. RITTER.
